UNITED STATES PATENT OFFICE.

WILLIAM McMEEN HEPBURN, OF NEW YORK, N. Y., ASSIGNOR TO SURFACE COMBUSTION COMPANY, OF NEW YORK, N. Y., A CORPORATION OF NEW YORK.

SEMIMUFFLE FORGE FURNACE.

Application filed April 30, 1927. Serial No. 187,782.

This invention relates to improvements in forge furnaces.

One of the objects of the invention is to provide a forge furnace which shall be particularly well adapted for heating one end of relatively elongated objects, for example, steel rods, one end only of which is required to be heated for the purpose of welding or shaping into one form or another as into bolt heads. Another object is to provide a forge furnace of such construction that while initial or preliminary heating of the work may be effected by causing burning gases to make intimate contact with the work, the final heating of the work may be done out of direct contact with the burning gases in order to avoid scaling or substantial oxidation of the work by the free oxygen or oxidizing gases which may be present in the burning gases.

Another object is to provide a forge furnace of such construction that the initial heating of the work may be effected not only by intimate contact with the burning gases but also indirectly by heat transmitted through the hearth or floor on which the work is supported. Another object is to provide a furnace of such construction that the work during its final heating may be surrounded by any desired atmosphere as, for example, a reducing atmosphere irrespective of the atmosphere existing in that part of the furnace where initial heating of the work is effected.

The above and other objects of the invention will more fully appear from the following detailed description taken in connection with the accompanying drawing wherein the preferred form of the invention is shown.

In the drawings

Fig. 1 is a longitudinal vertical section through the improved furnace, the view representing more or less diagrammatically the main features of the furnace, the view being taken on line 1—1 of Fig. 2;

Fig. 2 is in the main a horizontal section taken on line 2—2 of Fig. 1, some of the parts being in plan, and

Fig. 3 is a vertical transverse section taken on line 3—3 of Fig. 1, this view as well as Fig. 1 showing the work to be heated as consisting of round bars.

As shown in the drawings, the improved

forge furnace includes among other things, 55 a main furnace chamber into which burning gases are introduced, there being provided in said chamber an open-ended muffle having a floor which is extended to form a hearth on which the work is initially placed for preliminary heating. The furnace has been primarily designed for heating with gas. The gas is introduced into that end of the furnace which is adjacent the closed end of the muffle, the exit for the spent gases being 60 located at the other end of the furnace in order that the heating gases may pass forwardly over the muffle without entering the open end thereof.

The furnace chamber is indicated at 10, the 70 spent gas outlet at 12 and the burners at 14 of which a plurality are shown. In one side wall 16 of the furnace is a slot 18 through which the work pieces 20 may be introduced into and removed from the furnace. Ex- 75 tending laterally from side wall 16 in line with said slot 18 is the muffle, the roof of which is indicated at 22. This muffle does not extend the entire width of the furnace chamber. As shown in the drawings the 80 outer side wall 24 of the muffle is spaced from the adjacent side wall 26 of the furnace, thus providing a passage or space 28 which communicates with the upper and lower portions of the furnace chamber. It 85 may be stated at this point that the burners 14 are arranged to fire into the furnace chamber both above and below the muffle.

For convenience of description the muffle floor is designated by reference character 90 30. Extending forwardly from the muffle floor is a hearth 32 which, like the muffle, itself, extends laterally from the furnace wall 16 and in line with the slot 18. On this hearth the work is placed for preliminary heating by direct contact with the heating gases. The hearth and muffle floor are shown as of the same width. The outer edge of the hearth may be provided with an upstanding ridge 34 in alignment with the 100 muffle side wall 24 in order to prevent the work from being extended too far into the furnace whereby the free forward progress of the work into the muffle would be prevented.

The muffle floor 30 and its extension, i. e. the hearth 32, may conveniently be considered as a heat-permeable partition extend-

ing partially across the furnace chamber and the roof of the muffle as a heat-permeable shield.

The hearth 32 is preferably arranged to slope downwardly toward the muffle so that round work pieces placed on the hearth may roll by gravity into the muffle as the work pieces are withdrawn from the latter. The muffle floor preferably also slopes in the same direction as the hearth.

The furnace roof preferably slopes downwardly toward that end of the hearth 32 farthest removed from the muffle as indicated at 36, the flue 12 communicating with the furnace chamber at the lowest portion of the roof as indicated at 38. By sloping the roof in this manner the heating gases are forced downwardly toward the hearth as will be readily appreciated and are therefore caused to make intimate contact with the work pieces resting thereon before they pass out of the furnace through the flue 12. The hearth or floor 32 is in spaced relation with respect to the floor or bottom of the furnace chamber as is also the floor 30 of the muffle and consequently there is formed a combustion chamber below said hearth and muffle floor. As already indicated, burning gases are introduced into the furnace below the muffle and consequently the hearth will be heated from below with the result that the work pieces resting thereon are heated indirectly from below as well as directly from above.

As already indicated the burning gases are introduced into the furnace adjacent the closed end of the muffle and flow forwardly over the muffle without any tendency to enter the open end thereof. The atmosphere within the muffle is therefore for all practical purposes a stagnant and inert atmosphere and for this reason final heating of the work may be effected substantially free from scaling or oxidation such as would tend to occur if the work were to be brought to its final temperature in the open atmosphere of the furnace above the hearth where more or less oxidizing gases exist. While there may be some infiltration of air through the side opening or slot 18 through which the work pieces are removed from the muffle, nevertheless such air will not tend to flow very far into the muffle where the work pieces are hottest but due to the draft created by the flow of the heating gases through the furnace will rather tend to flow along the inside of the slot toward the spent gas outlet 12.

While the construction of the improved furnace is such that no substantial oxidation or scaling of the work will take place within the muffle it is oftentimes desirable to provide an atmosphere in the muffle which is substantially different from that which would ordinarily result during the normal

operation of the furnace. For example, it may be desirable to maintain a reducing atmosphere in the muffle. In order that any desired atmospheric condition may be maintained within the muffle I provide for the introduction into the muffle of such gases as will give the atmosphere desired. To this end I connect the closed end of the muffle with a conduit 40 which connects with a suitable pipe 42 outside of the furnace which pipe leads to a source of supply of raw gas or any other suitable gas adapted for the intended purpose. It will be readily appreciated that raw or reducing gas introduced into the muffle through the closed end thereof will pass forward over the work and out through the open end of the muffle and finally out through the spent gas outlet 12.

It should be noted that a furnace constructed in accordance with the present invention enables the greatest heat of the furnace to be localized where it is most desired, namely, along that portion of the muffle and hearth which extends farthest into the furnace chamber. This will be made more evident when it is pointed out that the burning gases introduced below the muffle must flow laterally thereof and into the space 28 and upwardly in order to pass out through the spent gas flue outlet 12. In the lower portion of the furnace chamber the circulation of the hot gases is more or less retarded by the furnace wall 16 and consequently relatively little heat is given up to the immediately adjacent parts.

It will now be readily appreciated that that part of the muffle chamber which extends farthest into the furnace will be subjected to the active circulation of the fresh hot gases and consequently that end of the work which extends farthest into the muffle will become the most highly heated by radiant heat from the muffle and furthermore that due to the manner in which the burning gases pass through the furnace, final heating in the muffle may be effected without appreciable or objectionable oxidation of the work.

What is claimed is:

1. The combination with a furnace chamber having an outlet for combustion gases at one end thereof, of an open-ended muffle therein having its open end facing the gas outlet end of said chamber whereby the heating gases tend to pass through said chamber without entering the open end of the muffle, the floor of the muffle being extended beyond its open end to form a hearth on which the objects to be heated may be initially placed for preliminary heating by the hot gases in said chamber, and independent firing means for introducing hot gases both above and below the muffle.
2. The combination with a furnace chamber having an outlet for combustion gases

- at one end thereof, of a muffle extending partially across the furnace chamber from one side thereof and having an opening in that end which faces the gas outlet end of said chamber for the introduction of work to be heated, and a hearth extending from the muffle floor longitudinally of said chamber for the initial reception of the work for preliminary heating before being passed into the muffle for final heating.
3. The combination with a furnace chamber having an outlet for combustion gases at one end thereof, of a muffle extending partially across the furnace chamber from one side thereof and having an opening in that end which faces the gas outlet end of said chamber for the introduction of work to be heated, a hearth extending from the muffle floor longitudinally of said chamber for the initial reception of the work to be heated in the muffle, said hearth extending only partially across said chamber.
4. The combination with a furnace chamber having an outlet for combustion gases at one end thereof, of an open-ended muffle therein having its open end facing the gas outlet end of said chamber whereby the heating gases tend to pass through said chamber without entering the open end of the muffle, the floor of the muffle being extended beyond its open end to form a hearth on which the objects to be heated in the muffle may be initially placed for preliminary heating by the hot gases flowing through said chamber, and independent firing means for introducing hot gases into the furnace chamber both above and below the muffle.
5. The combination with a furnace chamber having an outlet for combustion gases at one end thereof, of a muffle extending partially across the furnace chamber from one side thereof and having an opening in that end which faces the gas outlet end of said chamber for the introduction of work to be heated, a hearth extending from the muffle floor longitudinally of said chamber for the reception of objects to be preliminarily heated before being passed into the muffle for final heating, the furnace wall from which the muffle and hearth extends being provided with an elongated opening extending lengthwise of the muffle floor and hearth whereby those portions of the objects not required to be heated may extend outwardly of the furnace.
6. In a furnace, the combination of a combustion chamber having at one end thereof an outlet for combustion gases, a heat permeable partition extending lengthwise of the chamber intermediate the top and bottom thereof and of a width less than the width of said chamber whereby the upper and lower portions of said chamber are in free communication with each other, means for introducing combustible gases into said chamber, a heat permeable shield overlying a substantial portion of said partition, said shield starting from that end of the partition most remote from the outlet for the combustion gases and terminating intermediate the ends of said partition, said partition serving as a support for the objects to be heated and said shield serving to prevent combustion gases from making direct contact with the objects therebelow, and a passage communicating with the upper side of said partition to permit handling of the objects thereon from outside of the furnace.
7. In a furnace, the combination of a combustion chamber having at one end thereof an outlet for combustion gases, a heat permeable partition extending lengthwise of the chamber intermediate the top and bottom thereof and of a width less than the width of said chamber whereby the upper and lower portions of said chamber are in free communication with each other, means for introducing combustible gases into said chamber, a heat permeable shield overlying a substantial portion of said partition, said shield starting from that end of the partition most remote from the outlet for the combustion gases and terminating intermediate the ends of said partition, said partition serving as a support for the objects to be heated and said shield serving to prevent combustion gases from making direct contact with the objects therebelow, and a passage leading into the space below the shield whereby a fluid medium may be introduced into said space from a point exterior of the furnace chamber.
8. In a furnace, the combination of a combustion chamber, an open-ended muffle therein, a hearth extending in alinement with the muffle floor for the initial reception of the objects to be heated, means for supplying combustible gases adjacent the closed end of the muffle, a combustion-gas outlet adjacent that end of the hearth most distant from the muffle, a passage extending out of the furnace from the muffle through which passage a gaseous medium may be introduced into the muffle, and means through which work may be entered and removed from the furnace.
9. The combination with a furnace chamber having an outlet for combustion gases at one end thereof, of an open-ended muffle therein having its open end facing the gas outlet end of said chamber whereby the heating gases tend to pass through said chamber without entering the open end of the muffle, the floor of the muffle being extended beyond its open end to form a hearth on which the objects to be heated may be initially placed for preliminary heating by the hot gases in said chamber, said muffle and hearth being in vertically spaced relation with respect to the floor and roof of said chamber.

10. In a furnace, the combination of a fluid medium into said passage for flow 45
combustion chamber having at one end thereof an outlet for combustion gases, a heat
permeable partition extending lengthwise of
5 the chamber intermediate between the top and bottom thereof and of a width less than
the width of said chamber whereby the upper and lower portions of said chamber are
in free communication with each other,
10 means for introducing combustible gases into
said chamber, a heat permeable shield starting from that end of the partition most
remote from the outlet of the combustion
gases and terminating intermediate the ends
15 of said partition, said partition serving as
a support for the objects to be heated and
said shield serving to prevent combustion
gases from making direct contact with the
objects therebelow.
20 11. In a furnace, the combination of an
elongated chamber into which heating gases
may be introduced for the heating of objects
therewithin, a hearth along which the
objects to be heated may be progressed for
25 preliminary and final heating, said hearth
beyond that portion of its length necessary
for the preliminary heating of said objects
constituting the floor of a relatively shallow
passage into which said objects enter for
30 final heating, and means for supplying to
said passage a fluid medium for preventing
the entry of said heating gases into said
passage.
12. In a furnace, the combination of an
35 elongated chamber into which heating gases
may be introduced for the heating of objects
therewithin, a hearth along which the
objects to be heated may be progressed for
preliminary and final heating, said hearth
40 beyond that portion of its length necessary
for the preliminary heating of said objects
constituting the floor of a relatively shallow
passage into which said objects enter for
final heating, and means for introducing a
45
13. In a furnace, the combination of a
heating zone wherein combustion gases may
freely circulate, a hearth on which the ob- 50
jects to be heated may be exposed to direct
contact with said gasses, a passage open to
said combustion gases and into which pas-
sage the objects enter for final heating, and
means for introducing a fluid medium into 55
said passage to prevent the entry of said
gases into said passage.
14. A method of heating objects which
are progressed through a heating zone com- 60
prising preliminary heating said objects to
a point below their final temperature in the
presence of combustion gases, completing
the heating thereof in a passage tending to
prevent said gases from contacting with 65
said objects, and preventing the entry of
said gases into the passage by passing a
gaseous medium into the passage counter
current to the movement of the objects into
said passage.
15. A method of heating moving objects 70
comprising preliminarily heating the objects
in a gaseous atmosphere consisting of pro-
ducts of combustion, completing the heating
out of contact with said gases by passing the
objects into a passage containing a gaseous 75
medium which flows through the passage
counter current to the incoming objects.
16. A method of heating steel objects com-
prising initially passing the objects through
a zone containing combustion gases and be- 80
fore the objects attain an oxidizing tem-
perature passing them into a passage open to
said gases and preventing the entry of said
gases into said passage by causing a gaseous
medium to flow therethrough counter current 85
to the incoming objects.

In testimony whereof, I affix my signature,
WILLIAM McMEEN HEPBURN.
